UNITED STATES PATENT OFFICE.

FRANK H. HOUGHLAND, OF ST. LOUIS, MISSOURI.

BOX.

SPECIFICATION forming part of Letters Patent No. 681,323, dated August 27, 1901.

Application filed December 15, 1900. Serial No. 39,977. (No model.)

To all whom it may concern:

Be it known that I, FRANK H. HOUGHLAND, a citizen of the United States, residing at St. Louis, in the State of Missouri, have invented 5 a certain new and useful Improvement in Boxes, (Case B,) of which the following is a specification, reference being had to the accompanying drawings.

This invention relates to that class of boxes 10 or cartons shown and described in my application marked "A" and filed of even date herewith; and my object is to provide a box of that character which while being economical in construction will be capable of being 15 sealed and made thoroughly "germ-proof."

My invention therefore consists in the box or carton as illustrated in its preferable though not necessary embodiment in the accompanying drawings and described in detail hereinafter, and set forth by the claims at the end 20 hereof.

In the drawings accompanying this application, Figure 1 represents the blank from 25 which my box is made. Fig. 2 is a perspective view of the box partly made up and with the upper end partly closed, and Fig. 3 is a vertical central section.

Referring now to the details of the drawings by numerals, 1 represents the blank, 30 which is creased or scored entirely across its top and bottom at 2 and 3, thus dividing the ends from the sides. The blank is then creased or scored vertically at 4, 5, 6, and 7, and these two sets of creases form the sides 8, 9, 10, and 35 11, their gluing-strips 12, the ends 13, 14, 15, and 16, and 17, 18, 19, and 20. One-half of each of the end parts 13, 15, 17, and 19 and each of the parts 16 and 20 are made slightly smaller than the rest of the end parts for a 40 purpose to be hereinafter described, and between the parts 13, 14, and 15 and 17, 18, and 19 there is a small piece cut away, as shown in Fig. 1. The parts 13, 15, 17, and 19 are further creased or scored, as shown at 13^a, 45 15^a, 17^a, and 19^a, so that when the blank is made into box form the parts 13, 15, 17, and 19 may fold inwardly on these creases. The blank is folded or doubled on itself on the crease 6 and the pasting or gluing strip 12 50 secured to the inner edge of the side 11.

To set up the box, it is preferable to use a form or mandrel of rectangular shape of the

proper length, which is inserted within the rectangular opening formed by the sides 8, 9, 10, and 11. Then as the bottom is closed first 55 the operator presses his fingers against the triangularly-shaped part of the ends 13, 15, 17, and 19, formed by the creases 13^a, 15^a, 17^a, and 19^a, and forces them downwardly and inwardly, and by this simple operation the end 60 parts will be caused to assume the position shown in Fig. 2, in which the enlarged or projecting parts of the ends 17 and 19 are doubled under the enlarged part of the end 20. Glue is now spread on these enlarged portions, or, if desired, it may be spread within 65 the pocket formed by the folding ends on the opposite side, when the operator guides and directs these enlarged or projecting portions within said pocket and presses the ends down 70 flat. When the glue sufficiently adheres, the mandrel may of course be withdrawn, and we will now have a box or carton with its lower end absolutely sealed and which will be germ-proof and air-tight. After the mandrel is 75 withdrawn the box or carton is filled and the upper end sealed in a similar manner.

It is of course obvious that the mandrel is not necessary, but simply makes it easier and simpler to form the first end. It is also obvious that the projecting parts to be inserted within the pocket formed by the opposite end parts may, if preferred, be made much larger, so as to have a larger gluing-surface; but these and other details of my box may be varied without evading or departing from the spirit of my invention. 85

Upon referring to my drawings it will be observed that the parts 13, 15, 17, and 19 (each of which has been described as having a half 90 of smaller size) in reality have enlarged parts, which I have lettered 13^b, 15^b, 17^b, and 19^b, and I deem this construction as important for the reason that when the parts of the box are folded (see Fig. 2, where they are partially 95 folded) the said parts 13^b and 15^b fold under the gluing portion of the parts 14, and the parts 17^b and 19^b fold under the gluing portion of the part 18, and thus the end is doubled or reinforced at the point where it is 100 sealed or glued. This doubled or reinforced structure thus greatly increases the strength of the end closure, which of course is the most vulnerable part of a box.

From the foregoing it will be seen that I have produced a most simple carton which can be shipped absolutely flat and which when folded and packed end to end in a crate 5 will have a plurality of thicknesses or folds on each end, thus protecting the contents, and as there are no ends pasted on the top surface of the box there are no sharp corners on the outer surface which can form a starting place for ripping.

What I claim as new is—

1. A folded blank box having sides and ends made from a single blank having the parts of the ends of two sides toward the center of the 15 blank and the whole of one side extending beyond the main outlines of the blank, the

shorter ends being adapted and arranged to form a pocket to be entered by said extensions.

2. A blank for a folded blank box having 20 the inner parts of the ends of two sides and the whole of one side extending beyond the main outlines of the blank to form a pocket and entering-tongue to close the box.

In testimony whereof I affix my signature, 25 in the presence of two witnesses, this 5th day of December, 1900.

FRANK H. HOUGHLAND.
